Application December 21, 1931, Serial No. 582,289
Renewed June 4, 1934

5 Claims. (Cl. 120—34)

This invention relates to copy holders.

The present invention has for an object the provision of a copy holder which is simple of construction, has few moving parts, positive in operation, and inexpensive of manufacture.

With the present invention, I have provided a copy holder which will perform all the functions that may be performed by the most expensive type of copy holders now on the market and at a fraction of the cost of said copy holders. The present invention contemplates a suitable line guide which is movable at the will of the operator through simple mechanism which is readily adjustable as to the spaced movement of the line guide. I have also provided a line guide clutch, which is not subject to damage and which, under all circumstances, will always operate in a positive manner.

With the objects above mentioned, the invention further contemplates the novel and useful provision, formation, construction, association, and inter-relation of parts, members and features, all as shown in a certain embodiment in the accompanying drawings, described generally, and more particularly pointed out in the claims.

In the drawings:

Figure 1 is a front elevation of the improved copy holder,

Figure 2 is a rear elevation of the copy holder shown in Figure 1,

Figure 3 is a sectional view on the line 3—3 of Figure 2,

Figure 4 is a cross sectional view on the line 4—4 of Figure 3,

Figure 5 is a sectional view on the line 5—5 of Figure 3,

Figure 6 is a sectional view on the line 6—6 of Figure 4,

Figure 7 is a fragmentary view looking in the direction of the arrow 7 of Figure 2, and,

Figure 8 is a fragmentary view looking in the direction of the arrow 8 of Figure 2.

Referring now to the drawings, the improved copy holder includes a base or pallet 1 which may be of any size or shape and in the present instance is rectangular. The sides and bottom of the base are flanged as shown at 2, 3 and 4, in order to give rigidity to the base, and likewise for the purpose of accommodating and holding other elements of the invention. It is preferable to form the base from some metal and the flanges are accordingly formed by bending the metal in a triangular shaped manner. For instance, the side flanges would have two leg portions 5 and 6 in angular relation, with a leg portion 6 abutting

against the back of the base 1, see Figure 5. The bottom flange 4 would be similarly constructed with the exception that the angle between the legs 7 and 8 is more acute. The top edge of the base is likewise flanged by returnedly bending the metal in the manner best shown in Figure 3 at 9. It will thus be seen that the base 1 is not liable to be distorted or twisted, due to the presence of the flanges. The bottom leg 7 of the flange 4 is provided with one or more shock absorbing feet 10 and the rear surface of said base has secured thereto a block 11 provided with a pair of spaced knuckles 12 and 13 adapted to have secured therebetween a pedestal or leg 14 by passing a bolt 15 through aligned openings in the knuckles and arm. This pedestal or arm carries at one end a cushion foot 16. It is thus possible to set the base at selected angularities as, for instance, shown in Figure 3.

On the rear surface of the base and adjacent the flange 2 are a pair of spaced and substantially parallel rods 17 and 18. One end of both said rods is secured to a bracket 19, said bracket being secured to the base in any approved manner, as by the means shown at 20. This said bracket is adjacent the top flange 9 and the said bracket extends outwardly from the rear surface of the base and is provided with transverse openings 21 for receiving ends of the said rods 17 and 18. The bottom flange 4 and particularly the leg 8 thereof is provided with bores 22 adapted to permit passage therethrough of opposite end portions of the said rods 17 and 18. Thus, the said rods are held in position spaced from the rear surface of the base. Adapted for placement substantially intermediate the rods 17 and 18 and substantially parallel therewith is a feed rod 23. The bracket 19 is provided with a transverse bore 24 of slightly greater diameter than the diameter of the rod 23 and the rod 23 is in part received within said bore. The opposite end of the feed rod is bifurcated, as shown at 25. The flange 3 has both legs thereof provided with an aligned transverse bore, as shown at 26 and 27. The flange 2 has the leg 6 thereof formed with a transverse bore 28. Adapted to be passed through the transverse bores 26 and 27 and likewise through the bore 28 is an elongated rod 29 forming a part of an operating lever 30. Secured to this rod 29 in any approved manner is a lever 31 and an end of said lever is received between the bifurcations 25 of the feed rod and pinned thereto, as shown at 32. The operating lever 30 is formed by bending a rod so as to have a portion 33 substantially at right angles to the

rod 29, then returnedly and spacedly bending the rod so as to provide a part 34, the part 34 then terminating in an offset 35. The part 35 is screw-threaded as shown at 36 to receive a nut 37, the 5 end of the nut carrying a cushion foot 38.

It will be noted that the construction just described is such as to permit the operating lever to overlap the face portion of the base or pallet, to the end that the cushion foot may engage the 10 front face of the base, as shown in Figures 1 and 7. The lever 31 is flattened at 39 and which flattened portion is adapted to engage the inner face of the base, as best shown in Figure 3. This lever is also curved at 40 so that when the rod 15 29 is rotated, the lever will move upwardly, as illustrated in Figure 7 by the dotted line position 41, but will not move downwardly due to the face 39 of the lever engaging the case of the base. A coil spring 42 is secured between the 20 lever 31 and the flange 8, which normally maintains the lever in the position shown in Figure 3.

A clutch member 43 includes a block which is provided with two spaced transverse bores 44 and 45, a recessed or chamber portion 46, and a bore 47 communicating with the recessed portion. It 25 is intended that the guide rods 17 and 18 should be passed through the bores 44 and 45, respectively, and the feed rod passed through the bore 47 and beyond the chamber 46, as illustrated in Figure 4. The said block is provided with a pair of tapped bores 48 and 48a communicating with the bores 45 and 44, respectively, and both the said bores house friction means comprising, in each instance, a roller 49 against which bears a 30 spring 50 normally urging each respective roller against its respective guide rod. The spring and the roller are held within the said bores through the medium of a nut or the like 51. It will thus be seen that the block is in frictional engagement 35 with the guide rods so as to maintain the clutch member in adjusted positions relative to said guides. Within the chamber 46 is a one-way clutch 52, comprising a body piece 53 formed with an angular extremity 54. This body piece is provided with a transverse bore 55 which is slightly 40 elliptical in form, as illustrated in Figure 5. The angular extremity is adapted to have the end thereof resting against the base 56 bounding the chamber 46, and the feed rod 23 is passed 45 through said transverse bore 55. To properly enclose the block of the clutch member, I have provided a cover plate 57, which covers the front of said block and likewise the top thereof. This cover plate is held to the block, in any approved 50 manner, such as by providing tapped openings in the block and corresponding openings in the plate, whereby screws or the like may hold the plate to the block as, for instance, shown at 58 in Figure 2.

60 I may or may not have a coil spring 59 surrounding the feed rod 23 and included between the top portion of the cover plate and the member 52, for the reason that I have found that the device functions perfectly without the presence of said spring.

Secured to the cover plate 57 and extending outwardly therefrom is a bracket 60. This bracket is provided with a spring actuated corner hinge 61 and a line guide 62 comprising a flat metal strip adapted to overlie the face of the base, is secured to said spring hinge 61 and whereby the said line guide normally rests against the face of the base although the same may be moved outwardly therefrom, in the well understood manner.

I provide at 63 what I term a release lever, the same including a rod which is curvedly bent at 64, then provided with a portion 65 at right angles to the plane of the part 64, then a portion at 66 at right angles to the portion 65, the portion 66 having an end 67 at right angles thereto. 5

The clutch block is formed with a facial transverse groove 68 and the part 66 is received in said facial groove and held therein when the cover plate is in position. It is intended that 10 the angular extremity 67 should lie beneath the member 52, as best shown in Figure 4. The arrangement is such that when the release lever is moved upwardly to say the dotted line position at 69, the member 52 will be moved to the 15 dotted line position shown in Figure 4. I provide at 70 a sheet holder comprising an elongated rod 71 adapted to span the face of the base, said rod being bent at right angles to the elongated portion at 72 and 73, then again bent 20 at right angles to the parts 72 and 73, as shown at 74 and 75, then bent straight inwardly at right angles to the parts 74 and 75, as shown at 76 and 77, these portions passing through transverse openings provided therefor in the flanges 25 2 and 3, see Figure 2. The part 76 passes entirely through the flange 3 and the end thereof carries a block 78. Secured between the flange 9 and the base by any appropriate means is a leaf spring 79. The block 78 is adapted to engage 30 said leaf spring. Thus, this sheet holder may be tipped from the full line position to the dotted line position of Figure 3, the said block 78 engaging the spring 79 so as to permit this action to occur. 35

The operation, uses and advantages of the invention are as follows:

I may take an ordinary form of note book and lay the same over the top edge of the base, certain sheets being rearward on the base and other sheets engaged by the member 70 which would overlie the sheets. To hold the sheets on the reverse side of the base, I have provided a coil spring 80 transversely extending between the flanges 2 and 3, and this spring would overlie 45 said sheets. The line guide may be swung outwardly so as to overlie the sheets and the clutch member moved from say the position shown in Figures 1 and 2 to the topmost line of the page by lifting upwardly upon the release lever 63. 50 Having determined the proper spacing between lines of the copy, the nut 37 may be turned relative to the threads 36 so that the line guide may move a line at a time upon depression of the operating lever 30. When the operating lever is moved from the full line position of Figure 7 to the dotted line position, the feed rod will be moved upwardly from the full line position of Figure 7 to the dotted line position. This upward movement of the feed rod will produce no 55 movement of the clutch member but when the operating lever is allowed to move back from the dotted line position of Figure 7 to the full line position, the feed rod will be gripped by the member 52 and will move the clutch member downward a given amount. As stated, the clutch member is ordinarily held stationary due to the presence of the clutches carried by the body of the clutch member and engaging the guide rods 17 and 18. When the feed rod moves 60 upwardly the member 52 moves from the full line position of Figure 4 to the dotted line position which permits this rod to pass through the elliptical opening in the member 53 without moving the clutch member. However, when the feed rod 65 70 75 75

commences its downward motion due to pull thereon through the medium of the spring 42, the edge bounding the elliptical opening 55 immediately engages the surface of the feed rod 5 and commences downward movement with the said rod. It will be observed that the part 54 is engaging the base 56. As a consequence, pressure is exerted against the base through the member 54, which will move the block downwardly in step with movement of the feed rod. It is for this reason that the spring 59 may or may not be utilized.

After the line guide has completed its movement down the page, the line guide may be swung relative to its hinged spring so that a page of the note book may be turned and swung over the back of the base whereupon the operator may grasp the release lever, pushing straight upwardly thereon. The release lever 20 will turn slightly and the angular end 67 thereof will move the part 53 of the member 52 upwardly from the full line position of Figure 4, to the dotted line position, thus releasing said member 52 from the feed rod. The clutch member then 25 easily slides upon the guide rods 17 and 18 to any position selected, whereupon releasing the release lever, the device is ready for operation. As before stated, a turning of the member 37 will regulate the degree of depression permitted 30 to the operating lever, with the consequence that any degree of movement of the line guide desired is obtained.

It is obvious that various changes and modifications and variations may be made in practicing 35 the invention in departure from the particular showing of the drawings and description as given without departing from the true spirit thereof as defined by the appended claims.

I claim:

40 1. In a copy holder, a base, a pair of spaced substantially parallel guide rods secured to said base, a clutch member slidable upon said guide rods, friction means between said clutch member and one of said guide rods, a feed rod, a clutch 45 between said clutch member and said feed rod whereby when said feed rod is moved downwardly, said clutch member is moved on said guides, an operating lever for moving said feed rod, and means carried by said operating lever 50 for adjusting the degree of movement of said feed rod.

2. In a copy holder, a pallet, a line guide adapted to overlie the face of said pallet, a lever,

means between said lever and line guide whereby movement of the lever in one direction causes shifting of said line guide, and means on said lever for adjusting movement of the lever to in turn regulate shifting of the line guide, said means comprising a foot adjustably carried by the lever and adapted to contact with a face of the pallet when the lever is shifted in one direction.

3. The combination in a copy holder, of a 10 clutch member and a feed rod therefor, said clutch member including a block formed with a chamber portion, a one-way clutch in said chamber portion for engagement with said feed rod and whereby when the feed rod is moved 15 in one direction the clutch is released and when moved in a second direction the clutch is engaged to in turn move the clutch member, and a swing lever for engagement with said clutch to disengage the clutch to thereby shift the clutch 20 member independent of movement of the feed rod.

4. In a copy holder, a pallet, a guide rod secured thereto, a clutch member slidable upon said guide rod, friction means between said clutch 25 member and said guide rod, a feed rod, a clutch between said clutch member and said feed rod whereby when said feed rod is moved in one direction, said clutch member is moved on said guide rod, operating means for moving said feed 30 rod, said means comprising an oscillatable rod, a lever secured thereto, said lever being pivoted to one end of said feed rod, and resilient means normally urging said feed rod in one direction.

5. In a copy holder, a pallet, a guide rod secured thereto, a clutch member slidable upon said guide rod, friction means between said clutch member and said guide rod, a feed rod, a clutch between said clutch member and said feed rod whereby when said feed rod is moved in one 40 direction, said clutch member is moved on said guide rod, an operating lever for moving said feed rod; said operating lever including a rod carried by the pallet, a lever on said rod, said feed rod being secured to said lever; said second 45 lever having a part adapted to engage a surface of said pallet to limit rotation of said operating lever rod, and resilient means normally urging said last named lever into engagement with said pallet, to thereby maintain the feed rod in one 50 position.

CHARLES R. MERVYN.
